NON-CONTACTING ROLL CLEANING DEVICE
Herbert W. Heisterkamp, Cleveland, Ohio, assignor to
The Dow Chemical Company, Midland, Mich., a cor-
poration of Delaware

Filed Dec. 26, 1963, Ser. No. 333,523
4 Claims. (Cl. 118—70)

This invention relates to a non-contacting roll cleaning device, and a method for cleaning a sheet coating roll.

In the coating of certain sheet materials, such as with a latex solution, the coating is applied in a quantity greater than the desired coating thickness. This is done to insure full or adequate coverage over the entire sheet width. The coated sheet is then carried over a backing, or breast roll, where proper coating weight is achieved by the knifing action of an air jet. The excess coating material, which is sheared off to a collecting pan below, forms a dam directly below the contacting line of the air jet on the breast roll. The dam inevitably carries over the edges of the sheet with the result that the exposed breast roll is coated with the coating material which is knifed to a thickness approximating that on the film.

The coating on the roll partially dries due to air exposure which results in a gradual but continuous build-up of coating material adjacent each edge of the sheet being coated. This has at least two detrimental effects:

(1) The continuously wetted build-up is edged by the sheet but some inward flow along the roll may occur at the unwrapped portion on the breast roll. This allows coating material to flow underneath the sheet in uneven and perhaps heavy globs. Aside from drying problems, it presents problems in obtaining a good roll with the need for edge trim.

(2) The build-up continues until it reaches a depth equal to the gap between the air knife and the roll. Subsequently, contact with the air knife takes place, and debris in the form of small, dried particles of coating material, is sheared off and carried into the coating material pan, or directly onto the coated web, which adversely affects the quality of the coated web.

The apparatus of the subject invention corrects the foregoing coating problem. Briefly, the inventive concept involves the production of a negative, wetting atmosphere adjacent the edges of the sheet being coated. The ambient atmospheric pressure will cause a lifting of the wetted coating material on the roll adjacent the edges of the sheet, which lifted material will be conducted to a drain. In such manner, the danger of contamination of the coating material or the sheet being coated, is avoided. The apparatus which may be utilized to effect the realization of the inventive concept, does so in a simple and effective manner, and without physical contact with the roll being cleaned, thus avoiding any scratching, or marring thereof.

The main object of this invention is to provide a non-contacting roll cleaning device.

A more specific object is to provide a non-contacting roll cleaning device which is effective to remove residual coating material from a roll at each edge of a sheet being coated.

These and further objects and features of the invention will become more apparent from the following description and accompanying drawings wherein:

FIG. 1 is a plan view of apparatus embodying the principles of the invention;

FIG. 2 is a side view of the same;

FIG. 3 is a plan view, on a reduced scale, of the apparatus of FIG. 1 as operatively mounted upon a roll;

FIG. 4 is a section view generally as seen along line 4—4 in FIG. 1;

2

FIG. 5 is a section view generally as seen along line 5—5 in FIG. 1; and

FIG. 6 is a section view generally as seen along line 6—6 in FIG. 1.

Referring now to the drawings, a pair of cap, or cup elements 10 are positioned above a breast roll 12, as used in web coating apparatus, so that a curved peripheral edge of a lower open end 14 is maintained a short distance, such as 0.010", above the surface of the breast roll, as best seen in FIG. 4. The cup elements 10, which may be made of a non-metallic substance, such as Teflon, to avoid scratching the breast roll in event of contact therewith, are positioned so that the center lines thereof would coincide with the edges of a sheet of film 16 (FIG. 3). A manifold block 18 is positioned midway between the cups 10, said block being secured by pipes 20, 22, 24 and 26 which conduct water and air to and from the cups, as will be described in greater detail hereinafter. Pipes 20 and 22 straddle one of the cups 10, while pipes 24 and 26 straddle the other cup 10; a disc 28 is arranged for clamping the respective pipes on each cup so that the cups are maintained in operative position. Cap bolts 30 are provided for securing the discs 28 in position on the cups. It will be seen that the disc clamping arrangement will allow a lateral shifting of the cups 10 so that they may be adjusted to accommodate whatever width of film is being processed. Means (not shown) are provided for fixing the ends of the pipes 20, 22, 24 and 26.

Each cup 10 has a tapered recess 32 into which an air nozzle 34 protrudes in axial alignment with a pipe nipple 36 having a bell mouth inlet radius 38. The nozzle 34 and the pipe nipples 36 provide a venturi effect whereby the kinetic pressure of inlet air under compression flowing from the nozzle 34, is converted to static pressure which overcomes the flow friction in the discharge pipes 24 and 26. An axially arranged water inlet pipe 40 extends downwardly in the closed end of each cup 10 through a recess 42, the lower end of each pipe 40 being in spaced relation to an orifice 44. An annular opening 46 is thus provided for egress of compressed air. A passageway 48 is formed in each cup to conduct compressed air from the nozzle 34 to the recess 42. In such manner, air flowing out of the orifice 44, will mix with water flowing from the lower end of the pipe 40 to create a fog, or mist, within each cup recess 32.

The end of pipe 20 is threaded in a recess 48 in the manifold block 18, which recess serves hose, or tubing 50 adapted to conduct compressed air to the nozzle 34 of each cup 10. The end of pipe 22 is threaded in a recess 52 in the manifold block 18, which recess serves hose, or tubing 54 adapted to conduct water to the inlet pipe 40 of each cup 10.

An exhaust tubing, or hose, 56 is connected at one end to each pipe nipple 36, said tubing being connected at the other end to a recess 58 formed in the manifold block 18. In such manner, the fluid and air mixture in each cup recess 32 is carried to a drain, together with any web coating debris, or residual entrapped therein, by way of the pipes 24 and 26.

Operation of the above described apparatus is as follows. Compressed air, at approximately 30 p.s.i., is discharged through each nozzle 34 while water is conducted to the inlet pipe 40. The pressure of the water is not important. However, since the best fogging occurs with slight negative water pressure, it is preferred that water be conducted to inlet pipe 40 at a pressure slightly below that of the air emerging through the annular orifice 44 so that this air causes the induction of the water into recess 32 as a fog. Under such circumstance, it is substantially self regulating by its own design. Since a moist, negative atmosphere is maintained in each cup 10, suffi-

cient wetting of the coating material on the roll 12 is effected. Also, since the cup 10 has a sub-atmospheric pressure within its recess 32, the outside atmospheric pressure causes an air flow into the cup to carry residual coating material into the cup. Then, by reason of the fog within the recess, there is a dilution of such residual coating material so that it is discharged through tubing 56. Obviously, sufficient water must be introduced through nozzle 44 to insure adequate dilution of the coating material picked up so as to keep tubing 56 clear.

From the foregoing it will be seen that the apparatus described will satisfy all of the objectives of the invention.

The foregoing description has been given in detail without thought of limitation since the inventive principles involved are capable of assuming other forms without departing from the spirit of the invention or the scope of the following claims.

What is claimed is:

1. In combination with web coating apparatus including a roll over which a web is passed after having a coating material applied thereto and means cooperating with said roll to provide a uniform thickness of the coating material across the width of the web, the improvement comprising a non-contacting roll cleaning device for removing residual coating material on the roll on each edge of the web, said roll cleaning device including a pair of cup elements, each having an open end in uniform peripheral spaced relation to the surface of said roll, a liquid inlet means for admitting a liquid into the cup, an air inlet nozzle projecting into the cup, an air receiving pipe in spaced relation to said nozzle and in axial alignment therewith, passageway means arranged to conduct air from the nozzle to the liquid inlet means for mixing with liquid delivered into the cup to create fog

conditions in the cup, and means for conducting fluid material from within said cup elements to a drain.

5 2. A non-contacting roll cleaning device, as claimed in claim 1, wherein said air receiving pipe has a bell mouth inner end whereby a venturi effect is created by air flow coming from the nozzle and entering the receiving pipe.

10 3. A non-contacting roll cleaning device, as claimed in claim 2, further including a manifold block positioned between the cup elements, rigid pipe means for positionally maintaining the manifold block and the cup elements, and for delivering compressed air and water to the manifold block, hose means extending between the manifold block and each cup element for delivering compressed 15 air to the cup elements, an exhaust hose means extending between each cup element and the manifold block for conducting fluid material from within said cup element to a drain.

15 4. A non-contacting roll cleaning device, as claimed in claim 3, wherein said cup elements are laterally adjustable relative to each other.
